US00D862205S

(12) **United States Design Patent** (10) Patent No.: **US D862,205 S**
(45) Date of Patent: **** Oct. 8, 2019**

(54) **ZIPLINE TROLLEY**

(71) Applicant: **TruBlue LLC**, Boulder, CO (US)

(72) Inventors: **Carl Andrew Bailey**, Boulder, CO (US); **Ryan Daniel Walker**, Boulder, CO (US)

(73) Assignee: **TRUBLUE LLC**, Boulder, CO (US)

(**) Term: **15 Years**

(21) Appl. No.: **29/622,606**

(22) Filed: **Oct. 18, 2017**

(51) LOC (12) Cl. **09-06**

(52) U.S. Cl.

USPC **D8/356**

(58) **Field of Classification Search**

USPC D8/356, 354, 349, 360; D30/139; D11/218

See application file for complete search history.

Primary Examiner — Cynthia R Underwood

(57) **CLAIM**

The ornamental design for a zipline trolley, as shown and described.

DESCRIPTION

FIG. 1 is a perspective view of an exemplary zipline trolley according to the present disclosure;

FIG. 2 is a front view of the zipline trolley of FIG. 1;

FIG. 3 is a rear view of the zipline trolley of FIG. 1;

FIG. 4 is a right side view of the zipline trolley of FIG. 1;

FIG. 5 is a left side view of the zipline trolley of FIG. 1;

FIG. 6 is a top view of the zipline trolley of FIG. 1; and,

FIG. 7 is a bottom view of the zipline trolley of FIG. 1.

The broken lines represent environment or portions of the invention and form no part of the claimed design.

1 Claim, 7 Drawing Sheets
